WATER COOLER

Filed Jan. 9, 1928

The image contains five technical drawings of a device, labeled Tric. 1 through Tric. 5. Tric. 1 shows a top view of a rectangular frame with a central slot and a pen nib at the bottom. Tric. 2 shows a side view of the frame with internal parts labeled 10, 11, 12, 13, 14, 15, 16, 21, 22, 23, 24, 25, 26, 27, 28, 29, 30, 31, 32, 33, 34, 35, and 36. Tric. 3 shows a cross-section of the frame's interior. Tric. 4 shows a side view of the frame with internal parts labeled 10, 11, 12, 13, 14, 15, 16, 21, 22, 23, 24, 25, 26, 27, 28, 29, 30, 31, 32, 33, 34, 35, and 36. Tric. 5 shows a cross-section of the frame's interior. At the bottom, there is a signature that reads "MORRIS RAYMOND. INVENTOR" and "BY Victor J. Evans". The drawing is signed "G. W. Evans" at the bottom left. The bottom right corner contains the word "ATTORNEY".

UNITED STATES PATENT OFFICE.

MORRIS RAYMOND, OF BROOKLYN, NEW YORK.

WATER COOLER.

Application filed January 9, 1928. Serial No. 245,482.

This invention relates to improvements in water coolers for ice boxes and refrigerators.

The primary object of the invention resides in a water cooler for use in the ice compartment of a refrigerator and which is used in lieu of the ice tray for supporting the ice and for utilizing the waste water therefrom for cooling the drinking water within the cooler.

10 Another object is to provide a water cooler which is relatively flat and of a shape to fit into the ice compartment of a refrigerator and on which the ice is placed; the cooler having an upper drinking water compartment, and a lower ice water compartment into which the waste water from the ice drains, whereby the drinking water to be cooled is acted upon both by the ice and the ice water therefrom caused by the 20 melting ice.

A further object is the provision of an ice cooler for chilling drinking water which is especially adapted for domestic or home use, and which may be installed in the present 25 style of refrigerators without altering the construction thereof.

A still further object is to provide an ice cooler of the kind mentioned which may be conveniently filled with water for drinking 30 purposes and which may be easily washed and kept in a highly sanitary condition at all times.

With these and other objects in view, the invention resides in certain novel construction and combination and arrangement of parts, the essential features of which are hereinafter fully described, are particularly pointed out in the appended claims, and are illustrated in the accompanying drawing, 40 in which:—

Figure 1 is a vertical transverse sectional view through the ice compartment of a refrigerator showing my improved water cooler in position therein.

45 Figure 2 is a perspective view of the water cooler per se.

Figure 3 is a vertical sectional view on the line 3—3 of Figure 2.

Figure 4 is a similar view on the line 4—4 50 of Figure 2.

Figure 5 is a detail vertical sectional view on the line 5—5 of Figure 2.

Referring to the drawing by reference 55 characters, the numeral 10 designates my improved water cooler in its entirety which may be constructed of porcelain, or metal

coated with porcelain to prevent corrosion of the parts. The cooler includes a casing 11 which may be of any suitable shape to fit the particular refrigerator to which it is to be applied but which is shown as a relatively shallow rectangular casing in the drawing. The casing has spaced tubes 12 rising from the bottom wall thereof to an even plane with the side walls 13 thereof. Fitting over 60 the casing 11 is a lid or cover 14 having annular channels 15 for receiving the tops of the tubes 12 whereby the cover fits snugly down over the casing and closes the top of the same together with the tops of the tubes 70 12 which open through the casing bottom. The cover has a trough 16 around its edges and which trough is inclined toward one of the corners of the same where an outlet nipple 17 is provided. 75

Extending centrally from the bottom of the casing is a water outlet pipe 18 having a cock or valve 19 at the lower end thereof and by which the flow of water from the 80 casing is regulated.

The cover 14 has a filling opening 20 adjacent one of the front corners of the same for facilitating the easy filling of the casing with drinking water and which is closed by 85 a removable cap 21.

Suspended beneath and against the casing 11 is a tray 22 having flanges or brackets 23 thereon for vertical alignment with flanges or brackets 24 extending from the sides and bottom of the casing. Fastening 90 elements such as bolts 25 pass through the aligned flanges and receive retaining nuts 26. The tray constitutes an ice water compartment 27 for receiving the waste water drained from the top cover 14 when a cake 95 of ice is placed thereon for cooling the drinking water compartment 28 within the casing. The waste water from the melted ice drains from the cover through the nipple 17 into the compartment 27 through a pipe 29 rising from one corner of the tray and into which the nipple extends. The rear side of the tray has an outlet or overflow pipe 30 received in a recess 31 provided in the rear side wall of the casing and it is through this 100 drain pipe 30 that any excess water from the ice water compartment is carried off.

In practice, the ice cooler 10 is placed in the ice compartment 32 of a refrigerator 33 in lieu of the usual corrugated platform as 110 shown in Figure 1 of the drawing. The drain 30 overlies the drain pipe 34 of the re-

frigerator while the water outlet pipe 18 extends through the usual opening 35 in the bottom of the ice compartment so that the cock 19 is accessible through the door of the compartment below the ice compartment. When in position, the cake of ice for chilling the refrigerator is placed upon the cover 14 and by reason of the contact of the ice with the cover, the drinking water contained within the drinking water compartment is cooled thereby. The ice water from the melted ice sheds into the trough and passes into the ice-water compartment 27 and completely fills the same so that the underside of the drinking water compartment is subjected to the cooling action of the waste ice water. The level of the water in the compartment 27 is constantly maintained and any excess is carried off by the overflow pipe 30 which carries the water to the drain pipe 34 of the refrigerator. By subjecting the drinking water to the cooling action of the ice and the waste water therefrom, the same may be kept in a cool condition for drinking purposes. Warm air rising up from the compartment below the ice compartment 32 will enter the tube 12 and be cooled by the water in the compartment 28.

The casing 11 may be thoroughly washed by removing the cover 14 therefrom, as can the tray 22 by removing the fastening elements 25. The arrangement of parts facilitates the separation and cleaning of the same whereby the cooler may be kept in a clean sanitary condition at all times.

While I have described what I deem to be the most desirable embodiment of my invention, it is obvious that many of the details may be varied without in any way departing from the spirit of my invention, and I therefore do not limit myself to the exact details of construction herein set forth nor to any-

thing less than the whole of my invention limited only by the appended claims.

What is claimed as new is:—

1. A water cooler including a casing having a removable cover, an outlet pipe leading therefrom, a trough provided in said cover adjacent the side edges thereof, an ice water compartment beneath said casing, a drain pipe for carrying off water from said trough to said ice water compartment, and an overflow pipe leading from said ice water compartment for draining excess water therefrom.

2. A water cooler on which a cake of ice is adapted to be supported comprising a casing having a filling opening in the top thereof, a water discharge pipe leading from said casing, a trough provided about the top of said casing and being inclined toward a drain opening, an ice water compartment beneath said casing in communication with said drain opening for receiving any water from melted ice supported on top of said casing, and an overflow pipe leading from said ice water compartment for draining excess water therefrom.

3. A water cooler comprising a casing, spaced tubes opening through the bottom of said casing, a cover removably fitted to the top of said casing and closing the tops of said tubes, a trough provided in said cover adjacent the side edges thereof, a removable tray supported beneath the bottom of said casing, a passage between said trough and said tray, an overflow for carrying off excess water from said tray, an outlet pipe leading from said casing, and a control cock arranged in said outlet pipe, substantially as and for the purpose specified.

In testimony whereof I have affixed my signature.

MORRIS RAYMOND.
